UNITED STATES PATENT OFFICE.

EDNA L. WHITAKER, OF WEST BRANCH, MICHIGAN.

CLAMPING-BRACELET FOR MITTENS, GLOVES, &c.

1,377,648.

Specification of Letters Patent. Patented May 10, 1921.

Application filed May 12, 1920. Serial No. 380,841.

To all whom it may concern:

Be it known that I, EDNA L. WHITAKER, a citizen of the United States, residing at West Branch, in the county of Ogemaw and 5 State of Michigan, have invented certain new and useful Improvements in Clamping-Bracelets for Mittens, Gloves, &c., of which the following is a specification, reference being had to the accompanying drawings.

10 This invention relates to the art of gloves or mittens and the like, and particularly to an improved clamping bracelet for use in connection with the wrist portion of a mitten or glove, and one of the objects of the 15 invention is to provide a clamping bracelet of this kind, which is adjustable, so as to fit and clamp the mitten or glove or the like to wrists of different sizes.

A further object of the invention is the 20 provision of a clamping bracelet consisting of sheet metal, preferably aluminum, though not necessarily, for it is obvious that any other suitable metal may be used, there being adjustable connections between the ends 25 of the band to clamp the band or bracelet on the wrist, to prevent the mitten or glove from slipping off the hand.

A further object of the invention is the 30 provision of a mitten or glove having a folded portion to receive the bracelet in combination with a flap adjacent the folded portion of the wrist part of the mitten or glove, to cover the adjustably connected ends of the bracelet or band.

35 A further object of the invention is to provide rolled edges on the band or bracelet to prevent the metal from cutting the fabric or other material from which the mitten or glove is constructed.

40 A further object of the invention is the provision of an improved adjustable connection between the ends of the band or bracelet.

45 It is also the aim of the invention to provide a clamping bracelet for holding mittens or gloves on the hand to prevent the removal of the same and hence avoid thumb and finger sucking.

50 While the design and construction at present illustrated and set forth is deemed preferable, it is obvious that as a result of a reduction of the invention to a more practical form for commercial purposes, the invention may be susceptible to changes and the right 55 to these changes is claimed, provided they

are comprehended within the scope of what is claimed.

The invention comprises further features and combination of parts, as will be herein-after set forth, shown in the drawings and 60 claimed.

In the drawings:—

Figure 1 is a perspective view of a mitten, constructed in accordance with the invention and showing the bracelet or band arranged 65 in the folded part of the wrist portion of the mitten or glove and illustrating the flap closed.

Fig. 2 is an enlarged detail perspective view of the wrist portion of the mitten or 70 glove showing the flap raised, thereby illustrating the adjustable connections between the ends of the band or bracelet.

Fig. 3 is an enlarged detail perspective view of the band or bracelet removed; and 75

Fig. 4 is an enlarged detail horizontal sectional view on line 4—4 of Fig. 3 through the adjustable connections of the ends of the bracelet or band.

Referring more especially to the drawings, 1 designates a mitten or glove or similar wearing apparel, which may be constructed of any suitable material, leather, fabric of any kind, or the like. The wrist portion of the mitten or glove is folded and 85 stitched as shown at 2, in order to provide a channel for the reception of a bracelet or band 3, which may be constructed of any suitable metal, preferably aluminum, though not necessarily, for it is obvious that other 90 metals may be used. This bracelet or band 3 for the greater part of its length upon its opposite edges is provided with rolled portions 5, to prevent the band or bracelet from cutting the material, from which the mitten, 95 glove or the like is formed. These rolled portions are cut away near the opposite ends of the band or bracelet. One end 6 of the band or bracelet is provided with a threaded stud 7. The other end 8 of the 100 band or bracelet has riveted thereto as at 9 a plate 10. This plate is bent as shown at 11, so as to offset the body portion of the plate 10 from the outer face of the end 8 of the band or bracelet. This offset body 105 portion of the plate 10 and the end part 8 of the band or bracelet are provided with registering elongated slots 12 and 13. A thumb nut 14 is provided and which comprises a head 15 (which engages the outer faces of 110

the side of the offset portion of the body of the plate 10) and a base 16 (which is interposed between the offset body portion of the plate 10 and the outer face of the end part 5 of the band or bracelet). The head and base 15 and 16 are integrally connected by means of the contracted neck 17, which engages the elongated slot 12 of the offset body part of the plate 10. The thumb nut 10 is capable of longitudinal movement relatively to the slot 12. The thumb nut has a threaded socket 18 to receive the threaded stud 7, which passes through the slot 13 of the end portion 8 of the band or bracelet. 15 The band or bracelet is inserted through the channel of the folded part of the wrist portion of the glove, so that the end portion 8 of the band or bracelet may overlie the end portion 6 as shown, whereby the opposite 20 edges of the end portion 8 may engage between the rolls 5 adjacent the end portion 6 of the band. The end portions of the band or bracelet are so arranged, when the mitten or glove is applied to the hand, and the 25 band is drawn sufficiently tight about the wrist, after which the thumb nut is tightened, thereby drawing the two end portions 6 and 8 of the band or bracelet tightly together, hence clamping the wrist portion of 30 the mitten or glove in position, to prevent accidental movement of the mitten. The folded portion of the wrist part of the mitten is cut away, as shown, there being a flap 19 which may be folded over, whereby 35 by the thumb nut and the connection between the opposite ends of the band or bracelet are obscured from vision. This flap 19 is provided with the usual male and female fastening connection 20 with 40 the mitten or glove to hold the flap closed.

The invention having been set forth, what is claimed as new and useful is:

1. The combination with a hand wearing apparel, provided with a channel at its 45 wrist portion, of a band engaging through

said channel, one end of the band having a threaded stud, the other end of the band having an adjustable sliding thumb button carried thereby and provided with a socket to receive the threaded stud for clamping 50 the opposite ends of the band together.

2. The combination with a hand wearing apparel provided with a channel at its wrist portion, of a band engaging through said channel, one end of the band having a 55 threaded stud, the other end of the band having secured on its outer face an elongated plate having its greater portion offset and spaced from the outer face of the end of the band, said offset spaced body of 60 the plate and the end portion of the band being provided with registering slots, and a thumb button adjustable in the slot of the plate and having a portion intermediate the plate and the end portion of the band and 65 having a socket to receive the threaded stud to draw the two ends of the band tightly together.

3. The combination with a hand wearing apparel having its wrist portion provided 70 with a channel, of a band or bracelet engaging through said channel, the greater portion of the opposite edges of the band or bracelet being rolled longitudinally, one end of the band overlying the opposite end and 75 being slidably engaged between the opposing rolls of the band, and means adjustably connecting the opposite ends of the band, whereby the band may fit wrists of different sizes, the wrist portion of the hand wearing 80 apparel having a folding flap provided with a connection with the wearing apparel to cover the connections between the opposite ends of the band.

In testimony whereof I hereunto affix my 85 signature in the presence of two witnesses.
